UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

SUPERHEATER STEAM BOILER

Original application filed June 17, 1924, Serial No. 720,502. Divided and this application filed June 20, 1924, Serial No. 721,184. Renewed April 8, 1932.

My present invention relates to superheater steam boilers, and particularly those in which a superheater is exposed to radiant heat, and will be best understood from the following description and the annexed drawing, in which Fig. 1 is a section of a well-known type of boiler having a superheater embodying an illustrative form of my invention; Fig. 2 is an enlarged portion of Fig. 1; Fig. 10 3 is a section on the line 3—3 of Fig. 2; Fig. 4 is a section on the line 4—4 of Fig. 2; Fig. 5 is a view similar to Fig. 2, but showing a modification, and Fig. 6 is a section on the line 6—6 of Fig. 5.

15 My present application is a division of my application Serial No. 720,502 which was filed in the Patent Office on or about June 17, 1924.

20 Like reference characters indicate like parts in the several views.

25 In the illustrative arrangement, the boiler has uptake headers 10 and downtake headers 11 connected in the usual manner to a steam and water drum 12, the boiler tubes being arranged in two banks 13 and 14, with the tubes 14 extending across the furnace chamber 15 and the boiler being provided with baffles to direct the gases from the furnace chamber back and forth across the tubes to the gas 30 outlet.

35 A primary superheater 16, provided with an inlet header 17 and an outlet header 18 is located in the usual position above the boiler tubes 13, the inlet header 17 being connected by the pipe 19 to a pipe 20 connected to the steam and water drum 12.

40 In the illustrative arrangement, a radiant heat superheater is suspended from the lowermost row of the tubes 14 directly above the furnace chamber 15, this superheater comprising tubes 21 connected to an inlet header 22 and an outlet header 23, each located on opposite sides of the boiler with the superheater tubes 21 extending parallel to the 45 boiler tubes. As many of the superheater tubes 21 as desired may be supplied in the form illustrated up to the number of tubes 14 of the bottommost row. The superheater tubes 21 are arranged so as to have thermal contact with the boiler tubes to protect the

superheater tubes from excessive heating, particularly if for any reason, the heat conditions become such that the superheater tubes tend to become overheated. As one form of accomplishing this, I have provided 55 the tubes 14 in the lowermost row with projections 24, spaced along the tubes 14 and provided with a curved recess into which the superheater tube 21 fits snugly, so as to make a close contact between the superheater tube 60 and the projection 24. Obviously, the length and number of the projections 24 may be anything desired, according to the amount of heat it is desirable to transmit from the superheater tube 21 to the water tube 14.

65 In order to suspend the superheater tube 21 from the water tube, I have provided, in the arrangement shown in Figs. 2, 3 and 4, a series of loops 25, formed integrally with the superheater tube 21 and extending 70 around the water tube 14, these loops being arranged so as to hold the superheater tube 21 snugly against the projection 24. Preferably, also, the loops 25 are arranged so that if for any reason there is relative longitudinal movement between the water tubes 14 and the superheater tubes 21, due to different heat conditions in the two tubes, the loops 25 will permit this relative longitudinal movement without injury to either of the tubes. 75

80 In the modification shown in Figs. 5 and 6, the superheater tube 21 is held in position against the projections 24 by straps 26 extending around the two tubes, these straps functioning as will be obvious in the same 85 manner as the loops 25, but being unconnected to either of the tubes.

85 It will be obvious that the means for forming a thermal contact between the superheater tubes and the water tubes may be widely varied and that the particular form which I have shown is merely illustrative and that the same applies to the means by which the two tubes may be held in thermal contact.

90 A pipe 27 extends from the outlet header 18 of the primary superheater 16 to the inlet header 22 of the radiant heat superheater and a by-pass pipe 28 connects the pipe 20 with the pipe 27 at a point between the outlet header 18 and the inlet header 22. By this 95 100

arrangement, saturated steam from the drum 12 may be directed through the pipes 20 and 19 to the primary superheater 16 and from thence through the pipe 27 to the radiant 6 heat superheater tubes 21. Through the bypass pipe 28, saturated steam may be diverted around the primary superheater 16 and thus directly to the radiant heat superheater tubes 21. A valve 29 in the pipe 20 may be 10 provided to regulate the amount of saturated steam passing through the pipes 19 and 28.

While I have shown my invention in connection with a boiler having horizontally inclined water tubes, it will be obvious that it 15 may be applied to any other form of boiler, and that the embodiment thereof may be widely varied.

I claim:

1. In a steam boiler, a bank of superheater 20 tubes with at least a portion of each tube exposed to radiant heat from the furnace, and a row of boiler tubes parallel and adjacent the portions of the superheater tubes exposed to the radiant heat, and means to support each 25 superheater tube from one of said boiler tubes and hold said superheated tube and said boiler tube in close thermal contact.

2. In a steam boiler, a bank of superheater tubes with at least a portion of each tube exposed to radiant heat from the furnace, a 30 row of boiler tubes parallel and adjacent the portions of the superheater tubes exposed to the radiant heat, and means to support each superheater tube from one of said boiler tubes 35 and hold said superheater tube and said boiler tube in close thermal contact, said means being arranged to permit relative longitudinal motion between said tubes.

3. In a steam boiler, a bank of superheater 40 tubes with at least a portion of each tube exposed to radiant heat from the furnace, a row of boiler tubes parallel and adjacent the portions of the superheater tubes exposed to the radiant heat, and a plurality of loops for 45 each superheater tube extending around a water tube and arranged to hold said tubes in close thermal contact.

4. In a steam boiler, a bank of superheater tubes with at least a portion of each tube exposed to radiant heat from the furnace, a 50 row of boiler tubes parallel and adjacent the portions of the superheater tubes exposed to the radiant heat, and a plurality of loops for each superheater tube extending around a 55 water tube and arranged to hold said tubes in close thermal contact, and permit relative longitudinal motion therebetween.

5. In a steam boiler, a bank of superheater tubes with at least a portion of each tube exposed to radiant heat from the furnace, a 60 row of boiler tubes parallel and adjacent the portions of the superheater tubes exposed to the radiant heat, and means to support each superheater tube from one of said boiler tubes and hold said superheater tube and said boil-

er tube in close thermal contact, the exterior of each superheater tube and the corresponding boiler tube being shaped to provide a relatively large area of thermal contact between said tubes.

6. In a steam boiler, a bank of superheater tubes with at least a portion of each tube exposed to radiant heat from the furnace, a row of boiler tubes parallel and adjacent the portions of the superheater tubes exposed to the radiant heat, and means to support each superheater tube from one of said boiler tubes and hold said superheater tube and said boiler tube in close thermal contact, the exterior of each superheater tube and the corresponding boiler tube being provided with contacting portions shaped to provide a relatively large area of thermal contact between said tubes.

7. In a steam boiler, a bank of superheater tubes with at least a portion of each tube exposed to radiant heat from the furnace, a row of boiler tubes parallel and adjacent the portions of the superheater tubes exposed to the radiant heat, and means to support each superheater tube from one of said boiler tubes and hold said superheater tube and said boiler tube in close thermal contact, the exterior of each superheater tube and the corresponding tube being provided with contacting portions spaced along the tubes and shaped to provide a relatively large area of thermal contact between said tubes.

8. A steam boiler having horizontally extending water tubes above a furnace chamber, a superheater having tubes beneath the lowermost rows of boiler tubes and exposed to the radiant heat of the furnace and in thermal contact with the boiler tubes, said superheater tubes being parallel to the boiler tubes and each suspended from a boiler tube.

9. A steam boiler having horizontally extending water tubes above a furnace chamber, a superheater having tubes beneath the lowermost rows of boiler tubes and exposed to the radiant heat of the furnace and in thermal contact with the boiler tubes, said superheater tubes being parallel to the boiler tubes and suspension devices between each superheater tube and a boiler tube arranged to permit relative longitudinal movement between said tubes.

10. In combination, a furnace chamber, a superheater tube so placed as to be exposed to radiant heat from said chamber, a boiler tube disposed at least in part behind said superheater tube so as to be shielded thereby from the radiant heat of the chamber, and means for holding said tubes in close thermal contact with each other.

11. In combination, a furnace chamber, a superheater tube so placed as to be exposed to radiant heat from said chamber, a boiler tube disposed at least in part behind said superheater tube so as to be shielded thereby

from the radiant heat of the chamber, and means for holding said tubes in close thermal contact with each other and parallel to each other, said means being arranged to permit relative longitudinal motion between said tubes.

12. In combination, a furnace chamber, a superheater tube so placed as to be exposed to radiant heat from said chamber, a boiler tube disposed at least in part behind said superheater tube so as to be shielded thereby from the radiant heat of the chamber, and means carried by said water tube for holding said superheater tube in close thermal contact therewith.

13. In combination, a furnace chamber, a superheater tube so placed as to be exposed to radiant heat from said chamber, a boiler tube disposed at least in part behind said superheater tube so as to be shielded thereby from the radiant heat of the chamber, and means carried by said water tube for holding said superheater tube in close thermal contact therewith and parallel thereto, said means being arranged to permit relative longitudinal motion between said tubes.

14. In combination, a furnace chamber, a superheater tube so placed as to be exposed at least in part to radiant heat from said chamber, a boiler tube disposed adjacent said superheater tube and parallel thereto, and means for holding said tubes in close thermal contact with each other, said means being arranged to permit relative longitudinal motion between said tubes.

15. In combination, a furnace chamber, a superheater tube so placed as to be exposed at least in part to radiant heat from said chamber, a boiler tube disposed adjacent said superheater tube, and means for holding said tubes in extended thermal contact with each other.

16. A water tube steam boiler comprising a furnace chamber, a steam superheater tube having a substantial portion exposed to radiant heat from said furnace chamber, and a water tube arranged substantially in parallel and in extended intimate thermal contact with said superheater tube.

50 DAVID S. JACOBUS.
